DESIGN FOR A PLAYING CARD HOLDER

Rex E. Keller, Los Angeles, Calif.

Application June 26, 1933, Serial No. 48,542

Term of patent 14 years

To all whom it may concern:

Be it known that I, REX E. KELLER, a citizen of the United States, residing at Los Angeles, in the county of Los Angeles and State of California, have invented a new, original, and ornamental Design for Playing Card Holders, of which the following is a specification, reference being had to the accompanying drawing, forming part thereof.

Fig. 1 is a side elevation of the holder in closed position.

Fig. 2 is a side elevation of the holder in open position for affording access to the cards.

Fig. 3 is a top plan view of the holder in open position.

Fig. 4 is a sectional elevation of the holder in closed position, taken on line 4—4 of Fig. 3.

Fig. 5 is a sectional elevation of the holder in open position, taken on line 5—5 of Fig. 3.

I claim:

The ornamental design for a playing card holder, as shown.

REX E. KELLER.
